(57) **CLAIM**

The ornamental design for a liquor bottle, as shown and described.

DESCRIPTION

FIG. 1 is an exploded perspective view of the design for the liquor bottle;

FIG. 2 is a collapsed perspective view thereof;

FIG. 3 is an exploded front view thereof;

FIG. 4 is an exploded rear view thereof;

FIG. 5 is an exploded left side view thereof;

FIG. 6 is an exploded right side view thereof;

FIG. 7 is an exploded top view thereof; and,

FIG. 8 is an exploded bottom view thereof.

The broken lines are for the purposes of illustrating portions of the liquor bottle and form no part of the claimed design.
